J. P. WORTHINGTON

OIL WELL PUMP

Original Filed Feb. 23, 1926

UNITED STATES PATENT OFFICE.

JAMES P. WORTHINGTON, OF PONCA CITY, OKLAHOMA, ASSIGNOR OF ONE-HALF TO
LORY J. MILDREN, OF PONCA CITY, OKLAHOMA.

OIL-WELL PUMP.

Application filed February 23, 1926, Serial No. 90,120. Renewed April 14, 1928.

This invention relates to improvements in oil well pumps.

The primary object of this invention is the provision of a novel type of pump construction, preferably adaptable for use in the pumping of deep oil wells.

A further object of this invention is the provision of an improved oil well pump, adapted for use in connection with deep oil wells, embodying a rotary pump placed in

the oil well below the ground surface, with means operable from the surface in order to control said rotary pump, for the efficient pumping of oil in the lower end of the well.

15 A further object of this invention is the provision of an oil well pump, embodying a simple and economical arrangement of parts, which may be readily cleansed without de-

20 in the pumping of wells of considerable depth, and the same being adjustable to pump wells of various depths.

Other objects and advantages of this invention will be apparent during the course 25 of the following detailed description.

In the accompanying drawing, forming a part of this specification, and wherein similar reference characters designate corresponding parts throughout the several views,

30 Figure 1 is a diagrammatic representation of the improved oil well pump, showing the relative arrangement of parts thereof within the oil well.

Figure 2 is an enlarged fragmentary sectional view taken through the oil well pump construction, at that portion of the oil well pump construction which is located adjacent the lower end of the well, for the pumping of liquid upwardly in the well.

40 Figure 3 is a sectional view taken substantially on the line 3-3 of Figure 2.

Figure 4 is a fragmentary sectional view showing portions of the view illustrated in Figure 2, with an operating fluid medium 45 port in closed position, as used during the cleansing of the pump structure in the well.

Figure 5 is a sectional view taken substantially on the line 5-5 of Figure 4.

Figure 6 is a sectional view of the well 50 casing head.

In the drawing, wherein for the purpose of illustration is shown only a preferred embodiment of this invention, the letter A may generally designate an oil well, which receives inner and outer pipes B and C; the latter be-

ing adjustably positioned upon the upper end of the pipe B by means D. A motor operated pump E is preferably used for directing an operating medium from a reservoir F into either of the passageways of the 60 outer or inner pipes B or C, for control by deflecting and regulating means G operably positioned in the oil well, preferably adjacent the bottom thereof, at the lower end of the inner pipe C.

70 The well A may be lined with a suitable casing if desired, within which the pipe B may be positioned in stationary manner within the well A, with the upper end of the pipe B extending above the ground surface, and supported in any approved manner according to conventional practice. The outer pipe B has a passageway 20 therethrough, within which a deflector member 21 is mounted, which comprises a part of the 75 means G to be subsequently described; the deflector member 21 being positioned in the lower end of the inner pipe C, at the lower end of the well.

80 The inner pipe C is relatively smaller in diameter than the internal diameter of the passageway 20 of the outer pipe B, and it is supported axially in the passageway 20, by the means D which is mounted upon the top of the pipe B, and which is detailed in Figure 6 of the drawing. The pipe C is adjustably supported for relative movement in the passageway 20 by the means D, and the lower end thereof is provided with a tapered opening 22, above the deflector member 21.

90 The pump E is mounted at the top of the well, in any suitable manner, the same being provided with an inlet conduit 23, positioned in the sump or oil reservoir F wherein the operating medium is located. The pump E is 95 also provided with an outlet conduit 24 which enters the upper end of the outer pipe B, for the pumping of the impelling or operating fluid from the reservoir F directly into the passageway 20 at the upper end of the same, 100 for forced pumping downwardly thru the passageway 20 exteriorly of the inner pipe C, to the deflector member 21. Under normal operating circumstances the pipe C is positioned above the deflector 21 in spaced ports 105 providing relation, so that the impelling fluid may enter the inner pipe C and pass upwardly thru the passageway 26 thereof; the upper end of the inner pipe C extending at 27 above the supporting means D, and depend-

110

ing at 28 into a silencer 29 in the sump F so that the operating medium may be returned to the sump or reservoir F. During such a forced circuit of the oil from the sump F, the 5 motor or pump E is operated, as will be subsequently described, for sucking oil from the lower end of the well, upwardly into the passageway 26 of the inner pipe, where the same mingles with the operating fluid and together therewith is deposited in the sump F, where the same may overflow thru a line 30 to any suitable location.

Under some circumstances, as when cleaning the well, it may be desirable to close the 10 port means to prevent flow of oil between the passageways of the inner and outer pipes B and C, above the deflector member 21, and to this end the inner pipe C is rendered longitudinally adjustable in the passageway of the 15 outer pipe B, by the means D to be subsequently described. The operating medium from the reservoir F is then pumped in a bypassing relation directly into the passageway of the inner pipe C, thru a suitable by-pass 33. 20 This by-pass may be used independent of whether the port means is closed above the deflector 21, or not, for cleansing of details of the pump structure, by reversing the flow of operating medium. The by-pass 33 preferably 25 comprises a pipe portion 34 connected directly with the outlet 24, and a pipe portion 35 connected directly with the pipe C above the adjusting supporting means D, and telescopically related to the pipe means 34. 30 In the pipe C above the connection of the bypass portion 33 therewith a valve 37 is provided, which is closed during the by-passing operation, and a valve 38 is placed in the outlet 24 between the by-pass 33 and the outer 35 pipe B, to permit the pump E to by-pass the operating medium directly into the inner pipe C, so that it may be force-pumped downwardly thru the pipe C, and thence laterally thru the open port means above the deflector 40 into the passageway of the outer pipe B, and thence upwardly for a return to the sump or reservoir F, through a pipe line 39. 45 The deflector member 21 is preferably welded or otherwise secured within the passageway 20 of the outer pipe B, in the desired 50 location. It is ring-shaped, and has a central opening 40 axially aligned with the pipe B. The upper surface thereof is annularly concaved, at 41, between the periphery of the pipe B and the passageway 40, for deflecting the downward flow of the impelling medium laterally towards the axis of the pipe B; to operate the pump means G, as will be subsequently described. 55 A pump G at the lower ends of the pipes B and C, adjacent the bottom of the well A is operated by the impelling medium from the surface pump E, to create a suction in the well for withdrawing oil therefrom and forcing it upwardly through the inner pipe C. 60

It comprises an elongated tube 45, which may be conveniently divided into an upper portion 46, above the deflector 21, and a portion 47 below the deflector 21. This tube 45 is rotatably supported upon anti-friction upper and 70 lower bearing means 48 and 49, carried by the outer pipe B, below the deflector member 21.

The upper anti-friction means 48 may comprise inner and outer races 50 and 51, of ring-shaped formation, respectively welded or 75 otherwise secured upon the exterior surface of the tube 45 and the interior periphery of the pipe B, below the deflector member 21; the same having ball bearings 52 rotatably disposed between the same, and positioned to act 80 as thrust bearings.

The lower bearing means 49 similarly comprises inner and outer ring-shaped races 55 and 56, which are respectively secured, as by welding or screw threading upon the exterior surface at the lower end of the tube 45, and upon the interior surface of the pipe B at the lower end thereof, as illustrated in Figure 2 of the drawing. These races 55 and 56 have ball bearings 57 therebetween, and supporting the same so that the bearing 49 acts not only as a lateral bearing for the tube, but as a thrust bearing therefor. 90

The bearing structures 48 and 49 are of course spaced, in order to stably support the tube 45, for rotation, so that the upper end portion 46 is properly centered, against vibration. 95

The upper portion 46 of the tube 45 is of a diameter sufficient to permit the same to be rotatably received in a snug relation in the lower end of the passageway 26 of the inner tube C. The tube 45 above the bearing 48 extends thru the passageway 40 of the deflector 21, and immediately above the top surface of the deflector 21, the tube portion 46 is provided with a plurality of spaced parallel slots 60, in the nature of ports, for the passage of impelling fluid from the passageway of the outer pipe B, into the passageway 62 thru the upper tube portion 46, and thence into the passageway 26 of the inner pipe C, or for flow of the operating fluid in reverse direction to that mentioned. 100

As above mentioned the inner pipe C is adjustable, so that the lower open end therein may be adjusted relatively along the upper tube portion 46, downwardly or upwardly along the elongated ports 60 to the desired degree, to provide a regulated port communication between the inner and outer pipes B and C, or vice versa. If desired, the inner pipe C may be lowered sufficient to seat the tapered open end 22 thereof on the deflector seat 21, to close off communication between the passageways of the inner and outer pipes above the deflector 21. Normally, however, the parts will be as illustrated in Figure 2, for efficient operation. 115

In the passageway 62 of the tube portion 120

46, above the deflector 21, is placed a spiral screw or vane 67, which is formed on a shaft 68 extending axially thru the passageway 62; the peripheral edges of the spiral screw 67 5 being preferably in secured engagement at the inner periphery of the passageway 62, to provide a spiral way upwardly thru the tube portion 46, above the ports 60, thru which the impelling fluid must be forced from the passageway of the pipe B to the passageway of the pipe C, and thereby causing the tube 45 to 10 rotate in its bearings 48 and 49, as can readily be understood.

The impelling fluid being forced downwardly thru the pipe B and thence laterally over the deflector 21 thru the ports 60 and upwardly thru the tortuous way in the tube portion 46 and into the passageway of the inner pipe C, will cause a suction in the lower 15 end of the tube 45, sufficient to draw oil from the lower end of the well upwardly into the tube 45 for passage into the inner pipe C. To augment this lifting action, it is preferred to place a spiral vane or screw, or worm 70 in 20 the lower portion 47 of the tube 45. First, however, a tapered sleeve 71 is placed in the passageway of the tube portion 47, which has an upwardly tapering passageway 72 there-through with a diminishing diameter. In 25 this tapered passageway 72 is then placed the worm 70 and peripheral edges may be secured in the passageway 72. The worm 70 preferably has a shaft 73 extending axially thru the passageway 72 and thus a tortuous spiral way 30 is provided thru the lower portion 47 of the tube 45, which acts to lift the oil thru the tube 45, upon its rotation as above described.

Between the worms or spirals 67 and 70 and annularly projecting into the passageway 40 thru the tube 45, below the deflector 21, is provided a valve seat 80, having a passageway 81 therethrough. A ball check valve 82 is received upwardly upon this seat 80, to prevent back flow of impelling medium and 45 oil thru the opening 81; the upward movement of the ball valve 82 being checked by a cross bar or spider 83 of any approved formation. The ball valve 82 may be so formed that it will vibrate upon downward pressure in 50 the tube 46, incident to a reverse pumping of the operating fluid, to permit a portion of the fluid or oil to pass the check valve 82 into the passageway 72, for cleansing the same and 55 cleansing foreign materials from the spiral 70, which might become clogged thereon.

In order to guide the lowering of the detachable and adjustable pipe in proper centered relation with respect to the outer pipe B, and to receive the upper portion 46 of the 60 motor tube therein, it is preferred to provide a plurality of guide ribs or vanes 90, radially extending into the passageway 20 of the outer pipe B above the deflector 21, which at their inner edges are spaced from the center of the pipe B, a distance slightly greater

than the radius of the inner pipe C, to the external periphery thereof, so that the inner pipe C may be received between these free edges 91 in a sliding fit to prevent vibration. The upper portions of the guide ribs 90 project above the top edge 93 of the motor tube 45, and are convexly inclined at 94 in a converging relation from the inner periphery of the outer pipe B toward the center of the passageway thereof, to facilitate the centering of the pipe C, as it is lowered in the pipe B, and as can readily be understood.

The means D for adjustably supporting the pipe C within the stationary pipe B may comprise the construction illustrated in Figure 6, or may follow any approved construction such as that set forth in Patent #1,346,922, granted June 29, 1920. In the preferred supporting construction D, a supporting cap or block 95 is fixed upon the top of the pipe B above the ground surface, and this block 95 supports stationary bolts 96, which are threaded at their upper ends 97, for a distance along the length thereof. A supporting spider 98 is secured by wedge slips 99^a 90 to the upper end of the movable or adjustable pipe C, and this spider 98 is adjustably supported upon nuts 99 which are threaded on the portion 97 of the bolts 96. In order to adjust the pipe C, it is merely necessary to 95 elevate or lower the nuts 99, as can readily be understood.

The operation of the invention will be apparent from the foregoing. With the by-pass 33 closed, the pump E is operated to force the 100 impelling fluid from the reservoir F downwardly thru the passageway of the outer pipe B, and thence directed laterally thru the ports 60, by the deflector 21, and is forced upwardly thru the spiral way provided by the screw 105 67, and thus causing a rotation of the tube 46, of the pump G. The impelling fluid then passes upwardly thru the passageway 26 of the inner pipe, and returns to the sump F. This operation causes a suction in the tube 110 46, sufficient to lift the check valve 82, and cause a quantity of oil from the lower end of the well A to enter the tube 46, and pass the check valve 82, for mingling with the impelling fluid in the pipe C. Of course, the 115 worm 70 in the lower end of the motor tube 46 lifts the oil or other medium from the well.

A reverse flow of the impelling medium may be effected by closing the valves 37 and 38, thus shunting the impelling medium from the pump E thru the by-pass 33 directly into the upper end of the inner pipe C, and the same is forced downwardly and causes a reverse rotation of the motor tube 46. If the 125 ports 60 are open the impelling medium will pass laterally therethrough and return upwardly thru the passageway of the outer pipe B, and through the pipe 39 to the sump F. A portion of the oil will be forced past the check 130

valve 82, incident to vibration, due to the turbulent flow of the oil, upon the reverse pumping, and thus insuring that all parts of the pipe and motor and pump will be ⁵ cleansed of foreign sediments.

Various changes in the shape, size, and arrangement of parts may be made to the form of invention herein shown and described, without departing from the spirit of ¹⁰ the same or the scope of the claims.

I claim:

1. In a well pump the combination of an outer pipe having a passageway therethrough, an inner pipe having a passageway there ¹⁵ through, and located axially thru the passageway of the outer pipe, means for forcing an impelling fluid downwardly thru the passageway of the outer pipe, deflector means in the lower part of the passageway of the ²⁰ outer pipe for laterally deflecting the impelling fluid into the passageway of the inner pipe and upwardly therethrough, and motor means rotatably supported adjacent said deflector in the path of the impelling fluid for ²⁵ rotation thereby to create a suction thru the passageway of the pump below said deflector.

2. In a pump the combination of an outer pipe, an inner pipe, deflector means in the outer pipe below the inner pipe, means for ³⁰ pumping fluid downwardly thru the outer pipe, and over the deflector upwardly into the inner pipe, and a suction pump rotatably supported at the lower end of the inner pipe having a portion operably extending into the ³⁵ path of flow of the impelling fluid above said deflector to cause an operation of said suction pump for delivering fluid into the inner pipe.

3. In a well pump the combination of an outer pipe, an inner pipe within the outer ⁴⁰ pipe, a deflector carried by the outer pipe below the inner pipe, a pump rotatably supported by the outer pipe including a rotatable portion extending above the deflector into the inner pipe, said portion having transverse ⁴⁵ ports therein above the deflector, means for pumping an impelling fluid downwardly thru the outer pipe over the deflector and thence thru the ports into the portion of the pump above the deflector, and means in said portion ⁵⁰ of the pump above said deflector for causing rotation of the pump incident to travel of the impelling fluid therethrough, said pump below said deflector having a passageway there ⁵⁵ through open below the deflector.

4. In a well pump the combination of an outer pipe, an inner pipe within the outer pipe, a deflector carried by the outer pipe below the inner pipe, a pump rotatably supported by the outer pipe including a rotatable portion ⁶⁰ extending above the deflector into the inner pipe, said portion having transverse ports therein above the deflector, means for pumping an impelling fluid downwardly thru the outer pipe over the deflector and thence thru ⁶⁵ the ports into the portion of the pump above

the deflector, means in said portion of the pump above said deflector for causing rotation of the pump incident to travel of the impelling fluid therethrough, said pump below said deflector having a passageway there ⁷⁰ through open below the deflector, and a check valve in said passageway below the deflector.

5. In a well pump the combination of an outer pipe, an inner pipe supported in the outer pipe, a deflector in the inner pipe below the lower end of the inner pipe, said inner pipe being open at the lower end thereof, a tube rotatably supported by the outer pipe having a passageway therethrough, the tube extending thru said deflector and the tube ⁸⁰ having a passageway thereof open at the upper and lower ends thereof, said tube at its upper end extending into the lower open end of the inner pipe, said tube above the deflector having transverse ports to communicate the ⁸⁵ passageway of the outer pipe and the passageway of the tube below said inner pipe and above the deflector, means for forcing an impelling fluid downwardly through the outer pipe towards the deflector, and means in the ⁹⁰ passageway of the tube above said ports to cause a rotation of the tube as the impelling fluid passes upwardly thru said tube.

6. In a well pump the combination of an outer pipe, an inner pipe supported in the outer pipe, a deflector in the outer pipe below the lower end of the inner pipe, said inner pipe being open at the lower end thereof, a tube rotatably supported by the outer pipe having a passageway therethrough, the tube ⁹⁵ extending thru said deflector and the tube having a passageway thereof open at the upper and lower ends thereof, said tube at its upper end extending into the lower open end of the inner pipe, said tube above the deflector having transverse ports to communicate the ¹⁰⁰ passageway of the outer pipe and the passageway of the tube below said inner pipe and above the deflector, means for forcing an impelling fluid downwardly through the outer pipe towards the deflector, means in the passageway of the tube above said ports to cause a rotation of the tube as the impelling fluid passes upwardly thru said tube, and check valve ¹⁰⁵ means in the tube passageway below said ports to permit passing of a fluid upwardly there ¹¹⁰ through and prevent passing of a fluid downwardly therethrough.

7. In a well pump the combination of an outer pipe, an inner pipe supported in the outer pipe, a deflector in the outer pipe below the lower end of the inner pipe, said inner pipe being open at the lower end thereof, a tube rotatably supported by the outer pipe having a passageway there ¹²⁰ through, the tube extending thru said deflector and the tube having a passageway thereof open at the upper and lower ends thereof, said tube at its upper end extending into the lower open end of the inner pipe, said tube ¹²⁵

- above the deflector having transverse ports to communicate the passageway of the outer pipe and the passageway of the tube below said inner pipe and above the deflector, means 5 for forcing an impelling fluid downwardly through the outer pipe towards the deflector, means in the passageway of the tube above said ports to cause a rotation of the tube as the impelling fluid passes upwardly 10 thru said tube, check valve means in the tube passageway below said ports to permit passing of a fluid upwardly therethrough and prevent passing of a fluid downwardly therethrough, and a spiral blade in the passageway 15 of the tube below said check valve.
8. In a well pump the combination of outer and inner tubes having passageways therethrough, the inner tube being located axially through the passageway of the outer 20 tube, a deflector having a passageway therethrough located and carried by the outer pipe below the inner pipe, the inner pipe passageway being open at the lower end of said inner pipe at a point above said deflector, a tube, means carried by the outer pipe rotatably supporting the tube at a location below the deflector, said tube having an upper portion extending into the passageway of the deflector and upwardly into the passageway 25 at the lower end of the inner pipe, said upper portion of said tube having a spiral blade therein, said tube above the deflector having transverse ports connecting the interior of the tube with the passageway of the outer pipe, and means for adjusting the inner pipe longitudinally over said ports to regulate the opened or closed degree of communication thereof with respect to the passageway 30 of said tube.
10. In a pump the combination of an outer pipe having a passageway therethrough, an inner pipe having a passageway therethrough, means mounting the inner pipe in the outer pipe for longitudinal adjustment therein, deflector means mounted in the passageway of the outer pipe at a location below the inner pipe, and tubular means supported by the deflector means having a passageway aligning with the passageway of 35 the inner pipe and communicating therewith, the said tubular means having a port arrangement transversely therethrough adjacent the deflector means and over which port arrangement the lower end of the inner pipe is adjustable upon movement thereof longitudinally in the outer pipe to regulate the opening of the port arrangement in a communicating relation between the passageways of the outer and inner pipes.
9. In a well pump the combination of outer and inner tubes having passageways therethrough, the inner tube being located axially through the passageway of the outer 40 tube, a deflector having a passageway there-
- through located and carried by the outer pipe below the inner pipe, the inner pipe passageway being open at the lower end of said inner pipe at a point above said deflector, a tube, means carried by the outer pipe rotatably supporting the tube at a location below the deflector, said tube having an upper portion extending into the passageway of the deflector and upwardly into the passageway 45 at the lower end of the inner pipe, said upper portion of said tube having a spiral blade therein, said tube above the deflector having transverse ports connecting the interior of the tube with the passageway of the outer pipe, and means for adjusting the inner pipe longitudinally over said ports to regulate the opened or closed degree of communication thereof with respect to the passageway 50 of said tube.
10. In a pump the combination of an outer pipe having a passageway therethrough, an inner pipe having a passageway therethrough, means mounting the inner pipe in the outer pipe for longitudinal adjustment therein, deflector means mounted in the passageway of the outer pipe at a location below the inner pipe, and tubular means supported by the deflector means having a passageway aligning with the passageway of 55 the inner pipe and communicating therewith, the said tubular means having a port arrangement transversely therethrough adjacent the deflector means and over which port arrangement the lower end of the inner pipe is adjustable upon movement thereof longitudinally in the outer pipe to regulate the opening of the port arrangement in a communicating relation between the passageways of the outer and inner pipes.

JAMES P. WORTHINGTON.
